ABSTRACT OF THE DISCLOSURE

An output circuit comprises output current generating means controlled by an operational circuit and generating an output current corresponding to the output from the operational circuit, means for feeding the output current to a load through an impedance converting circuit and means for feeding back negatively a voltage accurately corresponding to the output current to the operational circuit. The output current is not affected by any variation in the load.

BACKGROUND OF THE INVENTION

This invention relates to an operational unit usable in industrial electronic control devices.

SUMMARY OF THE INVENTION

In the invention of subject application, an operational unit having a current input and a current output comprises; an input current source having an output terminal connected to a first reference potential line; an operational input resistance connected between another output terminal of the input current source and a second reference potential line having a voltage higher than that of the first reference potential line; a high gain operational amplifier having one of a pair of input terminals connected to the second reference potential line; an operational circuit consisting of a first operational impedance connected between one end of the operational input resistance and the other input terminal of the operational amplifier, and a second operational impedance having one end thereof connected to the other input terminal of the operational amplifier; an output current source having one output terminal connected to a third reference potential line having a voltage higher than that of the second reference potential line and adapted to generate a current signal corresponding to an output from the operational amplifier under the control of the output from the operational amplifier; a first transistor having an emitter thereof connected to another output terminal of the output current source through an operational output resistance, a base thereof connected to the second reference potential line, and a collector thereof connected to one end of a load having the opposite end thereof connected to the first reference potential line; a second transistor having a base thereof connected to a joint between the output resistance and the output current source, a collector thereof connected to the third reference potential line, and an emitter thereof connected to the operational circuit; an output circuit consisting of the first and the second transistors; and a bias current source having an output terminal connected to the third reference potential line and another output terminal connected to the other terminal of the input current source.

Therefore, a principal object of the present invention is to provide an operational unit having a current input and a current output.

2

Another object of the present invention is to provide an operational unit of the type fulfilling the aforesaid principal object, in which the output current is not affected by load variation and the negative feedback voltage is not influenced by temperature variation.

5 A further object of the present invention is to provide a novel operational unit capable of carrying out various mathematical operations simply by adding or removing suitable constituent elements.

10 BRIEF DESCRIPTION OF THE DRAWINGS

FIG. 1 is an electric circuit diagram of a mathematical operational unit provided in accordance with the present invention;

15 FIG. 2 is a block diagram showing transfer functions of the operational unit of FIG. 1;

FIG. 3 is a circuit diagram of an embodiment of the time delay circuit provided according to the present invention;

20 FIG. 4 is a circuit diagram of an embodiment of the differentiator provided according to the present invention; and

25 FIG. 5 is a circuit diagram of an embodiment of the integrator provided according to the present invention.

DESCRIPTION OF THE PREFERRED EMBODIMENTS

30 In FIG. 1, l_1 represents a first reference potential line, e.g., a ground potential line, l_2 a second reference potential line, e.g., a +12 volt D.C. line, and l_3 a third reference potential line, e.g., a +E volt (for instance, +24 volt) D.C. line. The symbol A designates a high gain operational amplifier having one of the pair of input terminals connected to a connecting point 5 on the second reference potential line l_2 and the other input terminal to another connecting point 4, respectively. Z_1 and Z_f are a first and a second operational impedance connected to connecting point 4 at one end thereof, respectively. R_1 is an operational input resistance connected between the second reference potential line l_2 and a connecting point 2 directly joined with an input terminal 1 of the operational unit. The opposite end of the first operational impedance Z_1 is connected to connecting point 2. An input current source CCS_1 is connected between input terminal 1 of the operational unit and the first reference potential line l_1 . The voltages of the third and of the second reference potential lines l_3 and l_2 are fed to the operational amplifier A through lead wires l_7 and l_6 , respectively. An operational circuit is formed by a combination of the operational amplifier A, the operational input resistance R_1 , and the first and the second operational impedances Z_1 and Z_f .

55 An output current source CCS_3 generates an output current I_o corresponding to an output 16 from the operational amplifier A, or the output from the operational circuit, and one of the pair of output terminals of the output current source connected to the third reference potential line l_3 while the other output terminal thereof to a connecting point 14, respectively. An operational output resistance R_o has one end thereof connected to connecting point 14, or to the other output terminal of the output current source CCS_3 .

60 A first transistor Q_1 , which is used as an impedance converter circuit, has a base connected to the second reference potential line l_2 , and an emitter connected to the other end of the operational output resistance R_o . A load R_L is connected between a collector of the first transistor Q_1 and the first reference potential line l_1 . In other words, the load R_L is connected to the output current source CCS_3 through

the impedance converter circuit and the operational output resistance R_o . A second transistor Q_2 of the output circuit generates feedback signals (a voltage V_f and a current I_f), which accurately correspond to the output current I_o , and provides means for feeding feedback signals to the operational circuit. The second transistor Q_2 has a base connected to connecting point 14, a collector connected to the third reference potential line l_3 , and an emitter connected to one end of an operational feedback resistance R_f has the opposite end thereof connected to connecting point 2. The emitter of the second transistor Q_2 is further connected to one end of the second operational impedance Z_f through a bias voltage source E_B . In the particular embodiment, illustrated in FIG. 1, the bias voltage source E_B comprises a constant-voltage diode D_2 , a resistance R_2 , and a potentiometer R_w shunting the diode D_2 , in which the diode D_2 and the resistance R_2 are connected in series with each other and inserted between the emitter of the second transistor Q_2 and the first reference potential line l_1 . Accordingly, the one end of the second operational impedance Z_f is connected to a sliding terminal of the potentiometer R_w . A constant voltage circuit for providing a constant voltage to the second reference potential line l_2 consists of a constant voltage diode D_1 and a resistance R_1 , in which the diode D_1 is connected between the first reference potential line l_1 and the second reference potential line l_2 , while the resistance R_1 is connected between the second reference potential line l_2 and the third reference potential line l_3 . A bias current source CCS_2 is inserted between the third reference potential line l_3 and input terminal 1 of the operational unit, to feed a bias current I_B to the operational unit.

The first transistor Q_1 is of a PNP type, while the second transistor is of an opposite NPN type, and both the first and the second transistors should preferably have a high gain. Those skilled in the art can easily conceive of a composite transistor of complementary connection and the like can be also used, depending on the case.

The operational amplifier A is a so-called negative high gain amplifier, and its operation is such that the output current I_o from the output current source CCS_3 increases when the input voltage thereto is reduced. The magnitude of the output current I_o from the output current source CCS_3 corresponds to the output signal from the operational amplifier A, and such output current source can be constructed by using a known transistor circuit, as apparent to those skilled in the art.

The operation of the circuit of FIG. 1 will now be described. For simplicity it is assumed the bias current and the bias voltage are nil, or $I_B=0$ and $E_B=0$.

When the output current source CCS_3 generates an output current I_o corresponding to the output from the operational amplifier A of the operational circuit, the output current I_o is fed to the first transistor Q_1 through the operational output resistance R_o . Since the first transistor Q_1 is in the form of the so-called base grounded transistor amplifier circuit with the base thereof connected to the second reference potential line l_2 , the almost entire current in the resistance R_o is fed to the load R_L through the emitter and the collector of the transistor Q_1 . As will be described hereinafter, the current flowing into the second transistor Q_2 is negligibly small, and hence, the output current I_o flows through the load R_L .

As described above, the second transistor Q_2 has a base connected to connecting point 14, a collector connected to the third reference potential line l_3 , and a emitter connected to the second reference potential line l_2 through the resistances R_f and R_1 in series, and accordingly, it forms a transistor amplifier of emitter follower connection, in which the input is the voltage drop $(I_o R_o + V_{be1})$ between connecting point 14 and the second reference potential line l_2 . The series connected resistances $(R_f + R_1)$ form a feedback resistance of the transistor amplifier. The negative feedback voltage V_f of the second transistor Q_2 , which appears between the emitter of the transistor

Q_2 and the second reference potential line l_2 , is given by the following equation.

$$V_f = I_o R_o + (V_{be1} - V_{be2}) \quad (1)$$

Here, V_{be1} and V_{be2} are base-emitter voltages of the first and the second transistors Q_1 and Q_2 , respectively. Such base-emitter voltages vary responsive to the ambient temperature variation, but in the particular circuit of FIG. 1, those base-emitter voltages of the transistors Q_1 and Q_2 are cancelled with each other, as shown by the Equation 1. As a result of it, by selecting the transistors Q_1 and Q_2 of suitable voltage drop characteristics, the term $(V_{be1} - V_{be2})$ can be made negligibly small. Thus, the Equation 1 can be simplified as shown by the following Equation 2.

$$V_f = I_o R_o \quad (2)$$

According to the Equation 2, the negative feedback voltage V_f accurately corresponds to the output current I_o , and it is not affected at all by any change in the base-emitter voltages of the transistors due to ambient temperature variations.

The magnitude of the negative feedback current I_f passing through the resistance R_f will now be determined. An input current I_i to the operational unit is fed from the input current source CCS_1 through the resistance R_i , which flows in the direction from the second reference potential line l_2 to connecting point 2. The negative feedback current I_f flows from the emitter of the transistor Q_2 to connecting point 2. Accordingly, the following Equation 3 can be derived.

$$I_f R_f - (I_i - I_f) R_1 + V_{be1} = I_o R_o + V_{be2} \quad (3)$$

By solving the Equation 3 for I_f ,

$$I_f = R_i I_i / (R_1 + R_f) + R_o I_o / (R_1 + R_f) + (V_{be2} - V_{be1}) \quad (4)$$

As explained above, the term $(V_{be2} - V_{be1})$ can be made negligibly small by selecting proper transistors Q_1 and Q_2 . Thus, the Equation 4 can be simplified to the following Equation 5, which shows that the negative feedback current I_f is not affected by the ambient temperature variation.

The input voltage V_i to the operational circuit is the

$$I_f = R_i I_i / (R_1 + R_f) + R_o I_o / (R_1 + R_f) \quad (5)$$

voltage drop across the operational input resistance R_i , which is given by the product of the resistance value R_i and the difference current $(I_i - I_f)$ between the input current I_i and the negative feedback current I_f . The input voltage V_i is applied to the input terminals of the operational amplifier A through the first operational impedance Z_i , while the negative feedback voltage V_f is applied to the input terminals of the operational amplifier A through the second operational impedance Z_f . As well known in the art, the operational circuit carries out the mathematical operation defined by the following Equation 6.

$$V_f = V_i (Z_i Z_f) \quad (6)$$

By substituting the Equation 5 defining I_f ,

$$V_f = (I_i - I_f) R_i$$

and $V_f = I_o R_o$ into the Equation 6, and by rearranging, the following Equation 7 can be derived to describe the relation between the input current I_i and the output current I_o .

$$(R_i / R_o) (Z_i / Z_f) (R_i / R_1 + R_f) I_i = (1 + (R_i / R_1 + R_f) (Z_f / Z_i)) I_o \quad (7)$$

Therefore, the transfer function of the operational unit, according to the present invention, can be given by the following Equation 8.

$$F(s) = \frac{I_o}{I_i} = \frac{R_f}{R_o} \frac{(Z_i / Z_f) (R_i / (R_1 + R_f))}{1 + (Z_i / Z_f) (R_i / (R_1 + R_f))} \quad (8)$$

FIG. 2 shows a block diagram of the transfer function of the operational unit of the present invention, as expressed in the Equation 8, in which each block represents

the corresponding term of the Equation 8 and the blocks are so assembled as to satisfy the relation of the Equation 8. As depicted in FIG. 2 and expressed in the Equation 8, the operational unit according to the present invention includes not only a fundamental operation circuit having a transfer function of Z_f/Z_1 , but also other operational factors having transfer functions $R_f/(R_1+R_f)$, $R_1/1/R_o$, and $R_o/(R_1+R_f)$, respectively. Thereby, a variety of different mathematical operations can be carried out by the unit.

FIG. 3 shows a circuit diagram of a time delay relay circuit embodying the present invention, which is similar to the circuit of FIG. 1 except that both the bias current source CCS_2 and the bias voltage source E_B are eliminated, while substituting a variable resistance R and a capacitor C for the first operational impedance Z_1 and the second operational impedance Z_f of FIG. 1, respectively.

The transfer function $F(s)$ for the circuit of FIG. 3 is given by the following Equation 9.

$$F(s) = K_p / (1 + TS) \quad (9)$$

Here,
 $K_p = R_f/R_o$,
 $T = RC(R_f+R_1)/R_1$, and
 $S = j\omega$, ω being the angular frequency of the input current I_i .

FIG. 4 shows a circuit diagram of a differentiator according to the present invention, which is similar to the circuit of FIG. 1, except that the bias current source CCS_2 is eliminated, while substituting a capacitor C and a variable resistance R for the first operational impedance Z_1 and the second operational impedance Z_f of FIG. 1, respectively. The following Equation 10 represents the transfer function for the differentiator of FIG. 4.

$$F(s) = T_D S / (1 + T_D S / K_D) \quad (10)$$

Here,
 $T_D = (R_f/R_o)(R_1/R_1+R_f)RC$,
 $K_D = R_f/R_o$, and
 $S = j\omega$

FIG. 5 shows a circuit diagram of an integrator according to the present invention, which is similar to the circuit of FIG. 1 except that the operation feedback resistance R_f of FIG. 1 is eliminated, while substituting a resistance R and a capacitance C for the first operational impedance Z_1 and the second operational impedance Z_f of FIG. 1, respectively. Furthermore, in the circuit of FIG. 5, a switch K is inserted between a connecting point 4 and the sliding element of a potentiometer R_w , and one end of the capacitor C is connected to the emitter of a second transistor Q_2 . The Equation 11 gives the transfer function $F(s)$ for the integrator of FIG. 5.

$$F(s) = 1/T_1 S \quad (11)$$

Here,
 $T_1 = (R_o/R_1)RC$, and
 $S = j\omega$

As described in the foregoing, according to the present invention, there is provided an operational unit comprising an operational circuit including a high gain operational amplifier A , an operational input resistance R_i , a first operational impedance Z_1 , and a second operational impedance Z_f ; an output current source CCS_3 for generating an output current corresponding to the output from the operational amplifier A ; an impedance converter circuit including a base grounded type transistor Q_1 ; a negative feedback means including another transistor Q_2 having a polarity opposite to that of the transistor Q_1 and adapted to generate a negative feedback voltage accurately corresponding to an output current I_o for applying the thus generated negative feedback voltage to said operational circuit; means R_f connected between the negative feedback means and an input terminal

of the operational amplifier, and adapted to feed a negative feedback current to said operational circuit, said negative feedback current being related to an input current I_i and the output current I_o of the operational circuit; and an output circuit consisting of said negative feedback means and the means R_f . The impedance converter circuit is made of base grounded type transistor circuit, hence, the input impedance thereof is low while the output impedance thereof is very high. Accordingly, the output current I_o delivered to the load through such impedance converter circuit is not affected by the load variation. It should be noted as another feature of the present invention that a negative feedback means including a first transistor and a second transistor having opposite polarities to each other is used, in conjunction with the aforesaid transistor type impedance converter circuit, so that the base-emitter voltages V_{be} of the two transistors are cancelled with each other. Thus, the negative feedback voltage accurately represents the output current I_o . In addition, such negative feedback voltage is not affected by the temperature variation. Besides, by adopting such circuit construction, in which not only the negative feedback voltage V_f but also the negative feedback current I_f are fed back to the operational circuit, a variety of different mathematical operations can be carried out by the operational unit, as shown by the Equation 8. For example, FIGS. 3 to 5 illustrate different operational units for different mathematical operations. In forming such different operational units, the number of circuit elements or parts is not increased, and such circuit construction can be completed simply by replacing a few circuit elements or reconnecting them. In other words, the modification can be made very easily.

Another feature of the operational unit according to the present invention is in that the common line or the second reference potential line I_2 is separated from the power source lines I_1 and I_3 , so that only signal currents I_i and I_f (which are in the order of several milliamperes to several ten milliamperes, as well known in the art) flows through the common line I_2 , without allowing passage of unnecessary currents therethrough, to suppress the voltage drop in the line I_2 caused by such signal currents to a negligibly low level. Thus, in spite of the fact that the operational unit of the present invention is driven by a single feeder line (in case of FIG. 1, the first and third reference potential lines I_1 and I_3), the influence of the error voltages generated across the resistances of the lead wires on the operational characteristics of the unit is negligibly small.

I claim:

1. An operational unit comprising an operational circuit consisting of a first reference potential line, a second reference potential line having a voltage higher than that of said first reference potential line, a third potential line having a voltage higher than that of said second reference potential line, a high gain operational amplifier having an input terminal connected to said second reference potential line, an operational input resistance connected between an input terminal of the operational unit and said second reference potential line, a first operational impedance connected between the input terminal of the operational unit and the other input terminal of said operational amplifier, and a second operational impedance having one end thereof connected to the other input terminal of said operational amplifier and the opposite end thereof so connected as to receive a negative feedback voltage; an input current source connected between the input terminal of the operational unit and the first reference potential line; a bias current source connected between the input terminal of the operational unit and said third reference potential line; and an output circuit; said output circuit comprising negative feedback means and an operational feedback resistance, said output circuit consisting of an output current source responsive to output signal from said operational amplifier for gen-

erating an output current corresponding to the output from said operational amplifier, an impedance converter circuit including a first transistor having a base thereof connected to said second reference potential line, an emitter thereof connected to an output terminal of said output current source through an operational output resistance and a collector thereof connected to a load, a negative feedback means including a second transistor of the opposite polarity to that of said first transistor and having a collector thereof connected to said third reference potential line, a base thereof connected to said output terminal of said output current source and an emitter thereof connected to the other end of said second

operational impedance through a bias voltage source, and said operational feedback resistance being connected between the emitter of said second transistor and the input terminal of said operational unit.
